BAG-TURNING MACHINE.

1,171,034.

Specification of Letters Patent.

Patented Feb. 8, 1916.

Application filed February 23, 1915. Serial No. 9,772.

To all whom it may concern:

Be it known that I, PETER J. GAGNON, Jr., a citizen of the United States of America, residing at South Lowell, Middlesex county, 5 State of Massachusetts, have invented an Improvement in Bag-Turning Machines; of which the following description, in connection with the accompanying drawing, is a specification, like characters on the drawing 10 representing like parts.

This invention relates to improvements in bag turning machines and the principal objects thereof are to provide a machine which may be adjusted for bags of different sizes and 15 lengths which will completely turn the bags inside out, leaving no unturned corners, also comprising means which will strip the bags from the turning members and deliver the same upon a suitable table, which preferably is rotatably mounted to receive the bags alternately end for end, and is provided with suitable means to permit it to 20 descend as the pile of bags thereon increases.

Many kinds of bags such as cotton bags 25 for sugar and salt, burlap bags for cement, grain, etc., are made from flat woven fabric folded and stitched along the sides and bottom to form the bag, the bag then being turned inside out so that the seamed edges 30 will lie within the bag and thus be protected, and its exterior present a smooth surface.

I am aware that heretofore bag turning machines have been constructed, but so far 35 as I am aware none has been devised which is adapted to turn bags of different sizes; which will smooth out the side seams throughout the length of the bags; and completely turn their corners; or which will 40 release the bags successively in such a manner that they will be stacked to form a neat and substantially level pile.

One of the principal features of this invention consists in the employment of parallel reciprocating bag engaging rods rounded at their ends, or preferably provided with enlarged spherical ends, adapted to press against the inturned edges of the bag, at least one of which is usually a seam, and thereby smooth out the seam throughout the 50 length of the bag.

Another feature of the invention resides in providing means for laterally adjusting

the parallel reciprocating bag turning members so that they will operate equally well 55 on bags of different sizes, and also in providing means for adjusting the extent of their reciprocating movement in order that they may operate properly upon bags of different depths.

Another feature of the invention consists in the employment of a stripping mechanism which will unfailingly grip and support the end of the bag as the reciprocating members are withdrawn and which may be 65 actuated to release the bag at the instant the turning members leave the mouth of the bag, so that the bag will drop horizontally upon a receiving table or upon the uppermost bag upon said table.

Another feature of the invention lies in the provision of means whereby the bags may be deposited on the pile successively end for end thereby maintaining the pile level notwithstanding the differences in 75 thickness of the edges and ends of the bag resulting from the inturned seams.

Another feature of this invention resides in providing a yieldable means for supporting the table which will permit the table 80 automatically to descend as the weight of the pile of bags thereon increases.

Another object of the invention is to provide a clutch mechanism which will permit the main driving shaft to rotate constantly 85 at a uniform speed, and which may be actuated by the operator to throw the bag turning mechanism into operation quickly as the upturned bag is presented by him to the turning devices.

Another object of the invention is to provide a machine which may be made principally from ordinary commercial materials such as rods, shafts, pipes, etc., with minimum expense but which when assembled 95 will afford a very rigid construction.

Other objects and features of the invention will more fully appear from the following description and the accompanying drawing which discloses a preferred embodiment of my invention and will be more fully pointed out in the annexed claims.

In the drawings: Figure 1 is a side elevation showing more or less diagrammatically the assembled construction of a bag 105 turning machine embodying my invention,

Fig. 2 is an end view of the machine observed from the plane indicated by lines 2-2 Fig. 1, Fig. 3 is a plan view of the machine, the central portion being broken away to permit the actuating mechanism and stripping mechanism to be illustrated in a single figure, Fig. 4 is a detail front elevation of the bag stripper, Fig. 5 is a side elevation of the same, and Fig. 6 is a detail view of a portion of the mechanism for actuating the stripper.

The operative parts of the bag turning mechanism are supported upon a frame which desirably comprises a cast iron shelf or beam 1 having upon its under side integral hollow cylindrical bosses 2, 3, 4, and 5 adapted to receive the ends of vertical metallic shafts or pipes of usual commercial construction and which may be secured therein by suitable set screws. Three of these shafts 6, 7, 8, constitute legs which support the shelf 1 and are seated at their bases in suitable sockets in cylindrical bosses 9, 10, 11 projecting upwardly from an integral base plate 12 which may be bolted to the floor.

The bag engaging and turning members preferably consist of a plurality, usually two, parallel cylindrical rods or plungers 13, 14 having rounded bag engaging ends, which desirably may be in the form of balls screwed upon their ends. The plungers 13, 14 are slidably mounted in bearings 15, 16 in stands 17, 18 adjustably mounted in a groove or way 19 in the upper side of the beam or shelf 1. The stands 17, 18 are provided with lateral extensions 20 having slots 21 through which bolts 22 seated in suitable bosses in the shelf 1 may extend, the stands being secured at any desired distance apart, to correspond to the width of the bags being turned, by tightening the nuts 23 of said bolts.

Inasmuch as the bag turning rods 13, 14 are necessarily of considerable length the bearings 15, 16 are provided with tubular extensions 24 of sufficient length to give them proper support. These extensions are desirably provided with raw-hide bushings 50 at their ends, and the bearings 15, 16 are provided with bronze bushings in order to reduce friction to a minimum, for it is obvious that a lubricant may not be used upon the plungers without danger of soiling the bags.

The bag turning plungers are actuated through a rod 25 forming a cross-head and having couplings 26 which may be adjustably secured to the plungers 13, 14 by set screws 27. The cross head 25 desirably is provided intermediate the couplings 26 with similar couplings having transverse apertures adapted to inclose and slide upon parallel supporting guide rods or tubes 28, 29, which are supported at one end upon a

bracket 30 carried by the shelf 1 and at the opposite end upon a bracket 31 carried by a vertical post 32. The post 32, like the legs 6, 7 and 8, may be of metal shafting or piping secured at its lower end within a cylindrical boss 33 extending upwardly from a base 34 bolted or screwed to the floor.

The cross-head 25, with the attached plungers 13, 14 desirably is reciprocated by a lever 35 having a slot 36 through which the cylindrical rod 25 forming the cross head passes, the lever being pivotally mounted upon a suitable pintle or stud 37 carried by a bracket 38 fixedly secured to the floor.

Any suitable means may be provided for oscillating the lever 35. A convenient means, which is illustrated herein, comprises a wheel or disk 40 having a stud 41 near its periphery connected by a suitable pitman 42 with a stud upon the median portion of the lever 35. The disk 40 is secured to a shaft 43 which is journaled in suitable bearings 44, 45 in brackets 46, 47 having grooved bases adapted to fit and be secured to the posts 7, 8 by caps 48 partially embracing said posts and clamped thereupon and to the brackets by suitable bolts 49.

In order to provide for the quick starting of the machine the shaft 43 desirably is driven through a friction clutch, which, as illustrated herein, comprises a fast pulley 50 keyed upon the shaft 43 and having a slightly conical face 51 and a co-operating, suitably driven, loose pulley 52 rotatably mounted upon the shaft 43 and having a peripheral flange 53 adapted to engage the conical face 51 of the pulley 50.

The pulley 52 is slidably mounted upon the shaft 43 and is moved into and out of engagement with the fast pulley by any usual shifting means. As illustrated herein it comprises a bell crank lever 54 pivoted at its elbow upon a stud 55 carried by a bracket 56 bolted to the base plate 12, the vertical arm of the lever being forked and secured by pins 57 to a suitable box 58 rotatably mounted in a groove 59 in the hub of the pulley 52. The end of the other arm 54' of the bell crank lever rests upon the arm 60 of a rock shaft 61 which is journaled in suitable bearings 62, 63 carried by the posts 6 and 7 and which is provided with an actuating arm 65.

The upper end of the arm 65 desirably may be provided with a handle but preferably is pivotally attached to a hook shaped arm 66 which rests in a suitable guide 67 carried by the post 6 and extends forwardly of the machine a sufficient distance so that its curved end may be pressed by the leg of the operator. For as will hereinafter more fully appear the hands of the operator are usually engaged in manipulating the bags

so that it is inconvenient if not impossible for him to use them to control the starting mechanism.

It will be obvious from the foregoing disclosure that when the operator presses the hooked arm 66 the loose driving pulley 52 will be forced into engagement with the fast pulley 50 thereby rotating the shaft 43 and wheel 40 to oscillate the lever 35, which in turn reciprocates the cross-head 25 and the attached plungers 13, 14.

A table 68^x which also may be supported on legs 68 of piping anchored in base plates 69 secured to the floor, may be provided to support the inturned bags.

In the operation of the machine the bags are first placed upon the table 68^x with the sewed ends of the bags toward the frame or shelf 1. The operator grasps the mouth of the uppermost bag and reverses or folds back the edge thereof over his thumbs in such a manner as to thrust the reversed portion over the balls of the plungers 13, 14. He then presses the starting lever, maintaining his hold upon the mouth of the bag. The plungers advance along the interior of the edges of the bag smoothing the seam or seams as they advance until they reach the bottom of the bag, finally forcing the corners into completely turned position. The operator then releases the bag which is thereupon automatically removed from the plungers by suitable stripping mechanism.

The preferred form of stripping mechanism disclosed herein comprises a pair of relatively movable clamping members adapted positively to engage the bottom portion of the turned bag and retain it in horizontal position in the plane of reciprocation of the plungers 13, 14 until they emerge from the mouth of the bag, mechanism being provided to release the clamping members at the instant the ends of the plungers pass from the mouth of the bag so that it will drop horizontally upon a suitable supporting table or upon the uppermost bag thereon. This requires a clamping mechanism which will positively grip the bag without slipping during the stripping operation, but which may be instantly and completely released from the bag at the end of that operation.

In the preferred embodiment of the invention disclosed herein the stripping mechanism comprises a pair of sharp prongs adapted to be thrust vertically into the bag adjacent to its corners and a coöperating pivotally mounted member adapted to be positioned horizontally beneath the bag as the prongs penetrate it, and to a return vertical position simultaneously with the withdrawal of the prongs. The mechanism which is illustrated in detail in Figs. 4 and 5 consists of a pair of horizontal diverging arms 70—71 bent at their outer ends to ver-

tical position and tapered and pointed to form prongs 72. The arms 70—71 are bent upwardly at their inner ends and secured to a sliding plate 74 by a suitable clamping plate 75 which is bolted to the slide 74. The slide 74 is mounted in a way in a stand 76, which is supported upon the upper end of a preferably cylindrical post 77 secured at the bottom to a base plate 78 screwed to the floor. The lower part of the stand 76 is provided with lateral extensions 79 which are vertically apertured to receive the ends of brackets 80 which are adjustably secured therein by suitable set screws 81. The lower end of the brackets 80 are bent forwardly beyond the plane of the sliding plate 74 and the ends of the same are connected by a cross bolt 82 adapted to serve as a pivot for the lower or coöperating clamping member of the bag stripping mechanism. This coöperating bag stripping member, which is adapted to engage the under side of the bag, preferably comprises a pair of diverging arms 83—84 arranged in parallelism with the arms 71—72 of the bag engaging prongs. These arms are preferably made from a single rod which is bent into U-shape, and the end portions bent in opposite directions to form the divergent arms, the intermediate portion 85 which is U-shaped in form being bent around the rod 82 so that the diverging arms 83—84 are pivotally mounted thereon. The U-shaped portion 85 desirably is curved downwardly as shown in Fig. 5 and is engaged by the lower end of the slide 74.

Inasmuch as the lower end of the slide 74 is a short distance beyond the rod 82 upon which the arms 83 and 84 are pivoted the descent of the slide 74 upon the curved U-shaped portion 85 will rock the rods 83—84 about the pivot 82 and raise them into engagement with the under surface of the bag simultaneously with the penetration of the prongs 72 into the bag so that the bag will be held firmly from longitudinal movement by the prongs 72 and will be maintained in horizontal position by the supporting rods 83—84.

When the slide 74 is raised the pressure is removed from the U-shaped portion 85 of the pivotal supporting member so that the arms 83—84 will drop simultaneously with the upward movement of the prongs 72—72 and will permit the bag to drop horizontally upon the table or pile in the manner aforesaid.

In order to properly release the bag when the ends of the plungers emerge from the mouth thereof as the cross-head is reciprocated it is necessary that the movement of the slide 74 be coördinated with the movement of the cross-head which actuates the bag turning plungers. This is accomplished in the present case by means of a rock shaft 130

86 journaled at its outer end in a bracket 87 extending laterally from the stand 76, said rock shaft having an arm 88 attached by a chain or other suitable connection 89 to a ring 90 upon the sliding plate 74, the rock shaft 86 being actuated by the cross head 25 near the forward and rearward ends of its stroke in a manner which will be herein-after described.

10 It is desirable that the plate 74 with its attached prongs may be easily removed from the stand 76 to sharpen the prongs, I have therefore attached the plate 74 to the stand 76 by slot and bolt connections, preferably comprising two slots 91—92 in the sliding plate which receive suitable bolts 93 extending upwardly from the stand 76, said bolts being provided with flattened thumb nuts 94 which when arranged longitudinally 15 of the sliding plate will pass through the slots but when arranged transversely thereof will slidingly retain the plate in place in the ways upon the stand.

The rock shaft 86 is supported at its inner end upon a bracket 95 extending from a vertical post 97, which preferably is in the form of a shaft 97 secured at its lower end in the boss 4 in the bed plate 1, the end of the bracket 95 being preferably so positioned that the rock shaft 86 lies parallel to the axial plane of the machine. The actuating arm 98 of the rock shaft 86 is connected by a vertical link 99 with the arm 100 of a bell crank lever which is pivoted at its elbow upon a stud 101 carried by a bracket 102 supported by the post 97. (See Figs. 2 and 6.)

40 The end portion 103 of the bell crank lever 100 is reduced and may preferably be cylindrical in form to engage a slot at the lower end of the rod 99. The end portion 103 desirably is bifurcated at its end and an anti-friction roller 104 journaled therein and adapted to bear upon the side of a leaf spring 105 bent into sinuous form at its upper end to provide hollows 106 and 107 adapted to receive the roller 104 and thereby hold the arm 100 of the bell crank lever in depressed or in elevated position in accordance with the movement of the cross head. The leaf spring 105 is suitably secured at its lower end by screws 108 passing through said spring 105 into the shelf 1 and a suitable boss or bracket 109 extending downwardly therefrom. The other arm 110 of the bell crank lever is provided with a stud 111 by which it is pivotally connected to the end of a rod 112, which is located above and extends parallel to the guide rods 28 and 29 which support the cross head 25, the other end of the rod 112 being slidably mounted in a suitable journal in the bracket 31 which is supported by the post 32, which also supports the outer ends of the rods 28 and 29. A helical cushioning spring 113 is

desirably secured to the end of the rod 112 in any suitable manner, for example, the end of the rod may be slotted to receive the final coil of the spring and a clamping nut screwed thereover.

76 In order to coördinate the movements of the stripping mechanism with the movement of the cross-head and to provide suitable means whereby such coördination may be retained notwithstanding the difference in 75 length of stroke for bags of different size, the rod 112 is provided near its ends with attached adjustable depending arms or brackets 114—115 suitably bent at their lower ends to lie in the path of the cross-head 25. These arms may be bifurcated at their upper ends and the bifurcation cylindrically bored to receive the rod 112 and may be clamped thereto by suitable screws 116 connecting the extended ends of said 85 bifurcations.

In the operation of the machine the brackets 114 and 115 are placed in such a manner that the cross-head 25 will engage them to reciprocate the rod 112 just as it reaches the extremity of its movement in either direction. When the cross-head moves forward therefore, and the bag turning members 13—14 almost reach the bottom of the bag the cross-head 25 engages the arm 95 114 moving the rod 112 forward, rocking the arm 100 of said bell crank lever downward, depressing the link 99 and through it the arm 98 of the rock shaft 86. The other arm 88 of the rock shaft, which is connected to 100 the slide 74, is simultaneously depressed, permitting the slide 74 to descend so that the prongs 72 will penetrate the bag. As the slide 72 descends it also contacts with the curved U-shaped extension 85 of the bag 105 supporting arms 83, 84 and raises them into contact with the bottom of the bag so that the bag is securely clamped by the time the ends of the plungers 13 and 14 reach the bottom corners of the bag. The cross-head 110 then moves in the opposite direction withdrawing the plungers 13 and 14 from the bag. As the ends of said plungers closely approach the mouth of the bag the cross-head engages the bracket 115, drawing the rod 112 in the opposite direction, raising the arm 100 of the bell crank lever and with it the link 99 and arms 98 and 88 of the rock shaft, and through the chain 89 raising the slide 74, thus withdrawing the prongs 72 from the bag. As the slide moves upwardly 120 it releases its engagement with the curved U-shaped portion of the supporting arms 83—84 so that the bag is permitted to drop horizontally.

125 It will be observed that by reason of the depressions 106 and 107 in the leaf spring 105 the arm 100 of the bell crank lever will be locked either in its depressed or in its elevated position until it is moved by the action 130

of the lever 112 so that the bag clamping mechanism is operated only at the ends of the stroke of the cross head.

Any suitable means may be provided to receive the bags as they are dropped by the stripping mechanism, if however the bags are piled one upon another with their seamed bottoms superposed the pile will become considerably thicker upon the seamed sides than upon the unseamed sides. I have therefore devised a table having means for intermittently rotating the same so that the successive bags will be deposited in reverse order, thus maintaining the pile level as it increases in height. I have also provided means for supporting the table which receives the bags thus discharged so that the surface of the table will be automatically lowered as the bags are piled upon it, and the distance between the uppermost bag and the stripping mechanism maintained substantially the same at all times, thereby providing for the more even piling of the bags. This is accomplished in the preferred form of the invention illustrated herein by providing a rotatable table so connected with the driving mechanism of the bag turning machine as to be rotated one half a revolution every time a bag is stripped. This table is supported by means of compressed air at such predetermined pressure that the additional weight placed upon the table as the successive bags are piled thereon will cause the table to descend in proportion to the building of the pile, hand operated means being provided to release the pressure if the weight of the bags on the table does not cause the table to be depressed sufficiently. This mechanism as illustrated herein comprises a table 120 supported upon a central standard 121 which extends into a compressed air cylinder 122 and has a piston head upon the lower end tightly fitting said cylinder. The cylinder 122 may be conveniently supported by a depending guide or bushing 123 from a base plate 124 secured to the floor. Compressed air may be introduced into the cylinder 122 through a pipe 125 leading from a suitable compressor 126, a cock 127 being placed at any convenient point in the pipe 126 and adapted to establish connection between the compressor and the cylinder, to shut off said connection, or to release the pressure in the cylinder as may be desired by the operator.

The table desirably is rotated through a worm gear 128 having an attached key 129 slidably mounted in a groove in the standard 121 of the table, said gear being retained in place by an L-shaped bracket 130 secured to the base plate 124 and having a bifurcated end extending above the gear and partly embracing the standard 121. The worm gear 128 desirably is rotated through a worm 131 journalized in suitable bearings 132 and 133

and connected by a universal joint 134 with a shaft 135 journaled at its opposite end in a bracket 136 secured to the vertical leg 7 of the frame. The shaft 135 is driven through a beveled gear 137 which meshes with a complementary beveled gear 138, which may conveniently be secured to or form a part of the disk 40 which actuates the lever 35 to reciprocate the cross head 25. In order that the table may be used without rotation I have provided a clutch 139 slidably keyed upon the shaft 135 and having a serrated face adapted to engage complementary serrations upon the hub of the gear 137 which is rotatably mounted upon the shaft 135.

It will be obvious that by providing the proper ratio of gearing the table 120 may be caused to move through one half a revolution upon each reciprocation of the bag turning plungers so that alternate bags may be deposited end for end upon the table, and that by suitably regulating the degree of pressure of the air in the compressed air pipe the table will be caused to descend in proportion to the weight of the bags placed thereupon, maintaining the top of the pile of bags at substantially a constant level as heretofore described.

The complete operation of the machine may be briefly described as follows: The bags to be turned are first placed upon the table 68* with the bottoms of the bags adjacent to the supporting frame and shelf 1, the plungers being withdrawn so that their ends are slightly closer to the shelf 1 than the mouths of the bags, the operator thereupon grasps the mouth of the uppermost bag with both hands, and turning the margin thereof over his thumbs, places the reversed mouth of the bag over the ends of the plungers 13, 14. He then presses the hooked arm 66 to start the movement of the plungers, maintaining his hold upon the top of the bag while the plungers advancing turn the outside of the bag inwardly. When the plungers have reached substantially the extent of their movement and are about to turn the corners of the bottom of the bag the cross-head engages the depending bracket 114 of the stripping mechanism causing the slide 74 to descend, thrusting the prongs 72 through the bag and simultaneously raising the supporting arms 83—84 into engagement with the under surface of the bag. The bag turning arms thereupon commence movement in the opposite direction, the bag being held firmly by the stripping mechanism. As the plungers are about to emerge from the mouth of the bag the cross head 25 engages the bracket 115, sliding the bar 112 in such a manner that it raises the arm 100 of the bell crank lever, and the link 99, thus raising the arm 88 of the rock shaft 86 and with it the slide so that the prongs are withdrawn from the bag and the supporting arms per-

mitted to drop just at the instant the plungers emerge from the mouth of the bag, thus permitting the bag to drop horizontally upon the table 120. Another bag is then presented by the operator to the plungers 13—14 and the operation repeated. In the meantime the table is rotated, through the gears 137, 138, the flexible shaft 135 and worm gears 131 and 128, one half a revolution so that the next succeeding bag falls upon the table with its mouth superposed upon the bottom of the preceding bag. As the bags accumulate upon the table they cause the depression of the table in proportion to the height of the pile so that the top of the pile is maintained at substantially the same level. If the weight of the bags is insufficient to depress the table in the manner aforesaid the operator may turn the cock 127 and release the compressed air sufficiently to permit the table to descend to the proper level. If, on the other hand, the table descends too rapidly under the weight of the bags a sufficient amount of compressed air may be admitted into the cylinder to raise the table to the desired level.

It is to be understood that the particular embodiment of my invention disclosed herein is illustrative merely, and that the several novel principles and features thereof may be embodied in different forms of mechanisms within the meaning and scope of the following claims.

This machine is not only adapted to turn bags in the manner aforesaid but may also be utilized to form double bags, that is to say, bags of double thickness. This may be accomplished by turning the first bag upon the plungers by hand while they remain stationary and thereafter by turning the second bag over the first with the plungers in motion as above described. This may also be accomplished by maintaining the stripping mechanism active during the first of the two operations aforesaid.

Having thus described my invention what I claim as new and desire to secure by Letters Patent is;

1. A bag turning machine comprising a plurality of bag turning members, means to reciprocate the same to cause them to engage, enter and while advancing reverse a positioned bag, means for gripping and holding the bottom end of the turned bag during the withdrawal of the bag turning members and means to release the bag gripping means from engagement with the bag when the bag turning members leave the mouth of the bag thereby to drop the bag horizontally.

2. A bag turning machine comprising a plurality of bag turning members, means to reciprocate the same to cause them to engage, enter and reverse a positioned bag, gripping means comprising members adapted to penetrate the bag and coöperating

supporting members adapted to hold the bag in horizontal position during the withdrawal of the bag turning members and means simultaneously to release the bag gripping means from the bag when the bag turning members leave the mouth of the bag.

3. A bag turning machine comprising a plurality of bag turning members, means to reciprocate the same to cause them to engage, enter and reverse a positioned bag, stripping means comprising a slide having a pair of pronged arms adapted to penetrate the bag and coöperating supporting members and means for simultaneously actuating said slide and said supporting members to grasp and hold the bag during the withdrawal of the bag turning means, and means for separating the prongs and supporting members as the bag turning members emerge from the mouth of the bag, whereby the bag may be dropped horizontally.

4. A bag turning machine comprising a plurality of bag turning members, a cross head connected to said members, means to reciprocate said cross head to cause said members to engage, enter and reverse a positioned bag, stripping means adapted to engage the bag when fully turned and to hold the bag during the withdrawal of the bag turning means and means actuated by said cross head adapted to release the stripping means as the bag turning members leave the mouth of the bag.

5. A bag turning machine comprising a plurality of bag turning members, a cross head connected to said members, means to reciprocate said cross head to cause said bag turning members to engage, enter and reverse a positioned bag, stripping means comprising a pair of separable members adapted to engage the bag when fully turned, means for actuating said members including a rock shaft connected to one of said members, a bell crank having one arm connected to said rock shaft, a sliding rod connected to the other arm of said bell crank and means carried by said sliding rod adapted to be engaged by said cross head as the same approaches the end of its movement in each direction, whereby said stripping means will be actuated to engage the bag at the conclusion of the turning movement of said members and will be actuated to release the bag when the turning members leave the mouth thereof.

6. A bag turning machine comprising a plurality of bag turning members, a cross head connected to said members, means to reciprocate said cross head to cause said bag turning members to engage, enter and reverse a positioned bag, stripping means comprising a pair of separable members adapted to engage the bag when fully turned, means for actuating said members including a rock

shaft connected to one of said members, a bell crank having one arm connected to said rock shaft, a sliding rod adjustably connected to the other arm of said bell crank and means carried by said sliding rod adapted to be engaged by said cross head as the same approaches the end of its movement in each direction, whereby said stripping means will be actuated to engage the bag at the conclusion of the turning movement of said members and will be actuated to release the bag when the turning members leave the mouth thereof.

7. Stripping mechanism for bag turning machines comprising a stand, a sliding member mounted thereon having vertically depending sharp prongs, a supporting member pivotally mounted upon said stand and having an offset portion adapted to be engaged by said sliding member to rotate said supporting member upon its pivot to cause the same to engage the under surface of the bag and means for actuating said sliding member.

25 8. Stripping mechanism for bag turning machines comprising a stand and sliding member mounted thereon having laterally extending arms provided with downwardly extended sharp prongs, a supporting member pivotally mounted upon said stand and having a curved extension positioned in the path of said sliding member and adapted to be engaged thereby upon the descent of said sliding member to cause the supporting member to rotate into engagement with the under face of the bag and means for actuating said sliding member.

9. Stripping mechanism for bag turning machines comprising a stand and sliding member mounted thereon having laterally extending arms provided with downwardly extended sharp prongs, a supporting member pivotally mounted upon said stand and having a curved extension positioned in the path of said sliding member and adapted to be engaged thereby upon the descent of said sliding member to cause the supporting member to rotate into engagement with the under face of the bag, means for actuating said sliding member, and means for detachably securing said sliding member to said stand whereby the same may be readily removed to permit the sharpening of the prongs.

55 10. Stripping mechanism for bag turning machines comprising a stand, a sliding member mounted thereon having laterally extending arms provided with downwardly extended sharp prongs, a supporting member pivotally mounted upon said stand and having a curved extension positioned in the path of said sliding member and adapted to be engaged thereby upon the descent of said sliding member to cause the supporting member to rotate into engagement with the

under face of the bag, means for actuating said sliding member, means for detachably securing said sliding member to said stand comprising a plurality of bolts rigidly secured in said stand and extending through slots in said sliding member, and having flattened members which when turned transversely of said slots will secure said member slidably upon said stand and when turned longitudinally of said slots will permit the removal of said member.

11. In a bag turning machine the combination of reciprocating bag turning members, stripping members, and a receiving table and means for positioning said table to receive successive bags in reversed position.

12. In a bag turning machine the combination of reciprocating bag turning members, stripping members, a table to receive the turned bags and means for rotating the table one half revolution upon each reciprocation of the bag turning members whereby successive bags will be piled upon said table in reverse order and a level pile of bags thereby maintained.

13. In a bag turning machine the combination of reciprocating bag turning members, stripping members, a table to receive the turned bags and means for rotating the table one half revolution upon each reciprocation of the bag turning members comprising a gear connected to the standard of said table, a worm coöperating with said gear, a shaft having a universal joint connecting the same with said worm, and means for actuating said shaft from the bag turning mechanism whereby said table will be rotated in synchronism with the reciprocation of said bag turning members.

14. In a bag turning machine the combination of reciprocating bag turning members, stripping members, a table to receive the turned bags and means for rotating the table one half revolution upon each reciprocation of the bag turning members comprising a gear connected to the standard of said table, a worm coöperating with said gear, a shaft having a universal joint connecting the same with said worm, a clutch on said shaft and driving mechanism adapted to be engaged by said clutch whereby said table may be rotated in synchronism with the reciprocation of said turning mechanism or may be released therefrom to permit the table to remain stationary.

15. A bag turning machine comprising parallel bag turning members, means to reciprocate the same to engage, enter, and reverse a positioned bag, stripping mechanism, a receiving table for the stripped bags, having a central standard terminating at its lower end in a piston, a cylinder for said piston, means for supplying compressed air to said cylinder and means for intermit-

tently rotating said table one half revolution in timed relation with each bag turning reciprocation of the bag turning members.

16. A bag turning machine comprising 5 parallel bag turning members, means to reciprocate the same to engage, enter, and reverse a positioned bag, stripping mechanism, a receiving table for the stripped bags, having a central standard terminating at its 10 lower end in a piston, a cylinder for said piston, means for supplying compressed air to said cylinder, means for manually controlling the compressed air supplied thereto whereby the supporting means may be 15 adapted to receive bags of different weight and means for intermittently rotating said table one-half revolution in timed relation with each bag turning reciprocation of the bag turning members.

17. In a bag turning machine the combination of parallel reciprocating bag turning members, stripping mechanism, means for actuating the same comprising a driving shaft, a driving pulley rotatably mounted thereupon, a friction clutch between said pulley and said shaft, means actuated by said shaft for actuating said bag turning members and said stripper and means operable by the leg of the operator to cause the engagement of said friction clutch. 20 25 30

In testimony whereof, I have signed my name to this specification, in the presence of two subscribing witnesses.

PETER J. GAGNON, JR.
